UNITED STATES PATENT OFFICE.

FRANK M. ARCHER, OF BROOKLINE, MASSACHUSETTS, ASSIGNOR TO THE MOXIE COMPANY, OF BOSTON, MASSACHUSETTS, A CORPORATION OF MAINE.

DESIGN FOR AN AUTOMOBILE.

50,373.

Specification for Design.

Patented Feb. 27, 1917.

Application filed November 21, 1916. Serial No. 132,543. Term of patent 14 years.

To all whom it may concern:

Be it known that I, FRANK M. ARCHER, a citizen of the United States, residing at Brookline, in the county of Norfolk and State of Massachusetts, have invented a new, original, and ornamental Design for an Automobile, of which the following is a specification, reference being had to the accompanying drawing, forming a part thereof, in which—

Figure 1 is a side view of the automobile; Fig. 2 is a top plan view of the automobile shown in Fig. 1.

I claim:

The ornamental design for an automobile, as shown.

Signed by me at Boston, Massachusetts, this 28th day of October, 1916.

FRANK M. ARCHER.
